UNITED STATES PATENT OFFICE.

CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

PROTECTIVE DEVICE.

Application filed March 7, 1919. Serial No. 281,165.

To all whom it may concern:

Be it known that I, CHESTER T. ALLCUTT, a citizen of the United States, and a resident of Pittsburgh, in the county of Allegheny and State of Pennsylvania, have invented a new and useful Improvement in Protective Devices, of which the following is a specification.

My invention relates to discharge gaps as used, for example, in lightning arresters, and it has for its object to provide apparatus of the character designated that shall operate selectively and permit current passage therethrough, preferably having a low current-impulse ratio, or, in other words, permitting the passage of high-frequency currents at equal or lower voltages than currents of normal frequency.

In the accompanying drawings, Figs. 1 to 4, inclusive, are diagrammatic views illustrating various forms of my invention, Fig. 4 showing the preferred construction.

In my former application, Serial No. 216,088, filed Feb. 8, 1918, I disclose apparatus functioning in this manner, an antenna being disposed between the main discharge electrodes and being connected thereto through impedance devices of dissimilar character, the adjustment being such that, at normal frequency, the drops in said impedance devices determine the potential of this antenna at a value substantially the same as that of the immediately adjacent electrostatic field. Upon a change in the frequency of the system, the drops in the two impedance devices change their relative ratio so as to cause the antenna to assume a potential different from that which the main electrodes strive to set up in the field immediately adjacent to the antenna. Thus, the antenna disturbs the electrostatic conditions with a change in the frequency and this effect may be so pronounced as to cause a given gap to break down with a high-frequency voltage far lower than the gap will hold at normal frequency.

My present invention embodies a modification of the structure described in my previous application for a special type of service, that is, for use on direct-current apparatus.

It will be obvious that, although the apparatus described in my previous application could be used on direct-current apparatus, the leakage of the condensers being

made such that they would maintain the antenna at the desired potential, a device specially adapted for direct current apparatus is desirable. Briefly, the present invention consists in replacing the devices specially adapted for alternating current by apparatus specially adapted for direct current.

Referring to Fig. 1 of the drawing for a more detailed understanding of my invention, I show a line wire 5 connected to a horn-shaped discharge member 6. A similarly shaped discharge member 7 is connected to ground at 8, either directly or through current-limiting devices, as may be desired. A small antenna 9 is mounted between the bases of the horns 6 and 7 and is connected to the horn 6 through a resistor 10 and a condensive reactor 11, and to the horn member 7 through a resistor 12. When the member 9 is disposed at the middle of the gap, the resistors 10 and 12 are of substantially equal value and serve to maintain the antenna at a potential midway between those of the horn members 6 and 7. The condenser 11 has a very small leakage and, therefore, when the frequency of the supply current in the line 5 is zero or direct current, the condenser 11 will have no effect upon the potential of the antenna 9. However, when a potential surge occurs on the line, due either to lightning or to a switching surge, the condenser will serve to raise the potential of the antenna member 9 to substantially that of the horn member 6, thus reducing the discharge gap to 50% of its former length, and, if the potential of the antenna 9 is raised high enough, a discharge will obtain between the discharge member 7 and the antenna 9, resulting in ionization of the entire discharge gap and a breakdown from the discharge member 7 directly to the discharge member 6. The resistance member 10 will aid in establishing the discharge between the members 6 and 7 on account of the fact that it offers constant resistance to the current passing through the antenna 9.

It will, of course, be obvious that the antenna member 9 could be placed closer to the one or the other of the discharge members 6 and 7, instead of midway between them, the only essential feature being that the resistance members 10 and 12 shall have values proportional to the distances to the respective discharge members.

In Fig. 2, I show a discharge gap in which

the condenser, shown mounted in parallel with the resistance 10 in Fig. 1, is replaced by an inductive reactor 13, connected in series relation with the resistor 12 and of such value that the potential drop across the resistor 12 and the inductive reactor 13 is substantially equal to the drop across resistor 10. With a structure of this character, a sudden surge of voltage will cause the potential of the antenna 9 to approach that of the discharge member 6, resulting in a discharge between the antenna 9 and the discharge member 7 if the potential of the member 9 approaches nearly enough to that of the discharge member 6.

In Fig. 3, I show one form which my invention may assume, wherein the antenna member 9 is connected to the discharge member 7 through a resistor 12. In this structure the leakage reactance of the member 14 must be equal to the resistance of the member 12 in order to maintain the antenna 9 at the proper potential under normal conditions.

In Fig. 4, I show the preferred form of my invention embodying the advantages of the structures shown in Figs 1 and 2 and consisting of a condensive reactor 11 in multiple with the resistor 10, as shown in Fig. 1, and also the inductive reactor 13 in series with the resistor 12, as shown in Fig. 2. The drops across the inductive reactor 13 and the resistor 12 in series and those across the resistor 10 and the condensive reactor 11 in multiple are proportional to the distance between the antenna 9 and the discharge members 7 and 6, respectively. A potential surge will cause the condenser 11 and the reactor 13 to co-operate to raise the potential of the antenna 9 to that of the discharge member 6, resulting in an initial discharge between the discharge member 7 and the antenna 9 and afterwards in a discharge between the discharge member 6 and the discharge member 7.

While I have shown my invention in a plurality of forms, it will be understood, by those versed in the art, that it is not so limited but is susceptible of various minor changes and modifications without departing from the spirit thereof and I desire, therefore, that only such limitations shall be placed thereupon as are imposed by the prior art or are specifically set forth in the appended claims.

I claim as my invention:

1. In electrical-spark-discharge-gap apparatus, the combination with two discharge members mounted in spaced relation to each other, of an auxiliary electrode mounted adjacent said discharge members, means embodying inductance connected between said auxiliary electrode and one of said discharge members, and means embodying resistance connected between auxiliary

electrode and the remaining discharge member.

2. In electrical-spark-discharge-gap apparatus, the combination with two discharge members mounted in spaced relation to each other, of an auxiliary electrode mounted adjacent said discharge members, means embodying resistance and inductance connected between said auxiliary electrode and one of said discharge members, and means embodying resistance connected between said electrode and the remaining discharge member.

3. In electrical-spark-discharge-gap apparatus, the combination with two discharge members mounted in spaced relation to each other, of an auxiliary electrode mounted adjacent said discharge members, means embodying resistance and inductance so arranged as to cause their impedances to be cumulative between said auxiliary electrode and one of said discharge members, and means embodying resistance connected between said auxiliary electrode and the remaining discharge member.

4. In electrical-spark-discharge-gap apparatus, the combination with two discharge members mounted in spaced relation to each other, of an auxiliary electrode mounted adjacent said discharge members, a connection between said auxiliary electrode and one of said discharge members embodying resistance and condensance connected in parallel relation, and a connection embodying resistance between said auxiliary electrode and the remaining discharge member.

5. In electrical-spark-discharge-gap apparatus, the combination with two discharge members mounted in spaced relation to each other, of an auxiliary electrode mounted adjacent said discharge members, and a connection embodying a resistor and a condenser connected in multiple relation between said electrode and one of said discharge members.

6. In electrical-spark-discharge-gap apparatus, the combination with two discharge members mounted in spaced relation to each other, of an auxiliary electrode mounted adjacent said discharge members, and a circuit embodying resistance and reactance connected between said auxiliary electrode and one of said discharge members, and a circuit embodying resistance and condensance connected between said auxiliary electrode and the remaining discharge member.

7. In electrical-spark-discharge-gap apparatus, the combination with two discharge members mounted in spaced relation to each other, of an auxiliary electrode mounted adjacent said discharge members, and a circuit embodying a resistor and a reactor connected in series relation between said auxiliary electrode and one of said discharge members and a circuit embodying a

resistor and a condenser connected in multiple relation between said auxiliary electrode and the remaining discharge member.

8. In electrical-spark-discharge-gap apparatus, the combination with two discharge members mounted in spaced relation to each other and connected to a supply circuit, of an auxiliary electrode mounted intermediate said discharge members, and a circuit embodying resistance and inductance connected between said auxiliary electrode and one of said discharge members, and means embodying resistance connected between said auxiliary electrode and the remaining discharge member, said circuits having impedances inversely proportional to the distances between the auxiliary electrode and the respective discharge members under normal operating conditions.
10. 9. In electrical-spark-discharge-gap apparatus, the combination with two discharge members mounted in spaced relation to each other and connected to a supply circuit, of an auxiliary electrode mounted intermediate said discharge members, and a circuit embodying resistance and capacitance connected between said auxiliary electrode and one of said discharge members, and means embodying resistance connected between said auxiliary electrode and the remaining discharge member, said circuits having impedances inversely proportional to the distances between the auxiliary electrode and the respective discharge members under normal operating conditions.
20. 10. In electrical-spark-discharge-gap apparatus, the combination with two discharge members mounted in spaced relation to each other and connected to a supply circuit, of an auxiliary electrode mounted intermediate said discharge members, and a circuit embodying resistance and capacitance connected between said auxiliary electrode and one of said discharge members, and means embodying resistance connected between said auxiliary electrode and the remaining discharge member, said circuits having impedances inversely proportional to the distances between the auxiliary electrode and the respective discharge members under normal operating conditions.
25. 11. In electrical-spark-discharge-gap apparatus, the combination with two discharge members mounted in spaced relation to each other and connected to a supply circuit, of an auxiliary electrode mounted intermediate said discharge members, and a circuit embodying resistance and reactance connected between said auxiliary electrode and the remaining discharge member, said circuits having impedances inversely proportional to the distances between the auxiliary electrode and the respective discharge members under normal operating conditions.
30. 12. In electrical-spark-discharge-gap apparatus, the combination with two discharge members mounted in spaced relation to each other and connected to a supply circuit, of an auxiliary electrode mounted intermediate said discharge members, and a circuit embodying resistance and reactance connected between said auxiliary electrode and the remaining discharge member, said circuits having impedances inversely proportional to the distances between the auxiliary electrode and the respective discharge members under normal operating conditions.
35. 13. In electrical-spark-discharge-gap apparatus, the combination with two discharge members mounted in spaced relation to each other and connected to a supply circuit, of an auxiliary electrode mounted intermediate said discharge members, and a circuit embodying resistance and reactance connected between said auxiliary electrode and the remaining discharge member, said circuits having impedances inversely proportional to the distances between the auxiliary electrode and the respective discharge members under normal operating conditions.
40. 14. In electrical-spark-discharge-gap apparatus, the combination with two discharge members mounted in spaced relation to each other and connected to a supply circuit, of an auxiliary electrode mounted intermediate said discharge members and a circuit embodying resistance and reactance

connected between said auxiliary electrode and one of said discharge-gap members and a circuit embodying resistance and capacitance connected between said auxiliary electrode and the remaining discharge gap member, said circuits having impedances inversely proportional to the distances between the auxiliary electrode and the respective discharge members under normal operating conditions.

15. 11. The combination with an electrical-spark-discharge-gap device comprising two spaced discharge members one of which is connected to a source of electromotive force and the other of which is connected to a circuit to which it is desired that the source of electromotive force be connected when the discharge gap breaks down, of an auxiliary electrode mounted adjacent to said discharge members and conductively connected to both of said discharge members through impedance devices.

16. 12. The combination with an electrical-spark-discharge-gap device comprising two spaced discharge members, one of which is connected to a source of electromotive force and the other of which is connected to a circuit to which it is desired that the source of electromotive force be connected when the discharge gap breaks down, of an auxiliary electrode mounted adjacent to said discharge members and conductively connected to both of said discharge members, and means for causing the impedance between said auxiliary electrode and one of said main electrodes to change upon an alternating current being impressed upon said source of electromotive force.

In testimony whereof, I have hereunto subscribed my name this 19th day of Feb., 1919.

CHESTER T. ALLCUTT.
